UNITED STATES PATENT OFFICE.

CHARLES HUBER, OF NEW YORK, N. Y., ASSIGNOR, BY MESNE ASSIGNMENTS, TO
TRIPLEX MANUFACTURING CO., INCORPORATED, A CORPORATION OF NEW YORK.

DESIGN FOR A GAS-SAVING ATTACHMENT FOR GAS-STOVES.

46,401.

Specification for Design.

Patented Sept. 15, 1914.

Application filed June 1, 1914. Serial No. 842,320. Term of patent 7 years.

To all whom it may concern:

Be it known that I, CHARLES HUBER, a citizen of Switzerland, and a resident of the city of New York, borough of Manhattan, in the county and State of New York, have invented a new, original, and ornamental Design for a Gas-Saving Attachment for Gas-Stoves, of which the following is a specification, reference being had to the accompanying drawing, forming part thereof, and in which—

Figure 1 is a perspective view of the gas saving attachment; and Fig. 2 is a sectional view thereof.

I claim:

The ornamental design for a gas saving attachment for a gas stove, as shown.

CHARLES HUBER.
